Attorney

UNITED STATES PATENT OFFICE.

WILLIAM F. KASSEBAUM, OF HEBRON, NEBRASKA.

FOLDABLE WICKET FOR DAMS.

1,404,969.

Specification of Letters Patent. Patented Jan. 31, 1922.

Application filed June 21, 1921. Serial No. 479,412.

To all whom it may concern:

Be it known that I, WILLIAM F. KASSEBAUM, a citizen of the United States, residing at Hebron, in the county of Thayer and 5 State of Nebraska, have invented a new and Improved Foldable Wicket for Dams, of which the following is a specification.

This invention relates generally to improvements in wicket dam structures and 10 more specifically has reference to an improved foldable bracket or wicket, and primarily my invention has for its purpose to provide an improved dam structure of the general character stated of a relatively inexpensive nature and which is especially designed for being used on the top of cement 15 or other forms of water dams so as to provide for adjusting the dam of water, and for collapsing all of the brackets that constitute a part of a dam section or gate to drop onto the dam top to allow the free escape of surplus water.

Another object of my invention is to provide a simple and easily actuated means for 20 releasing all of the wicket or bracket members connected with a gate or dam section, in unison, and for dropping flatwise along the top and inner edge of the dam wall, out of the way along such wall top, and in 25 which the bracket members are so formed that when the dam or gate section is swung up the brackets automatically open out and lock themselves to their extended position so as to hold the bracket or gate at the 30 proper place.

With other minor objects in view, that will hereinafter be apparent, my invention comprises a foldable bracket or wicket for 35 dam sections that embodies the peculiar features of construction and arrangement of parts, fully set out in the following detailed description, specifically mentioned in the appended claims and illustrated in the accompanying drawings in which:

40 Figure 1 is a perspective view of a dam wicket section with my improved foldable wicket or bracket members, the same being shown as operatively mounted on the top of the dam wall.

45 Figure 2 is a similar view and it illustrates the gate section dropped and the gate brackets to the folded or collapsed adjustments.

50 Figure 3 is a vertical cross section taken

substantially on the line 3—3 of Figure 1, 55 and

Figure 4 is a perspective view of one of my improved brackets detached from the 60 gate or wicket wall.

In the practical development of my invention, my improved bracket is made out 65 of strips of strap metal, preferably steel, about two inches wide and about one-half inch thick, and in practice, four or five of such brackets, set about four feet apart, are 70 attached to each wicket or gate section, the several brackets for each gate section being adapted for collapsing or folding down at the same time when it is desired to drop the gate, as will hereinafter be fully explained. 75

Each bracket includes, what is hereinafter termed a base member 1, and an upright member 2 whose lower end is connected to the outer end of the base member 1, by a hinge 3 that is designed to permit the upright 75 2 to drop inwardly upon the said base member 1 when the gate is lowered, as is clearly shown in Figure 2 of the drawing.

In practice the base member 1 of the bracket is of sufficient length to extend 80 crosswise the full width of the top of the dam wall and its inner end is extended to form an angled portion 10 that fits over the inner edge α of the dam wall top, see Figure 3. 85

The portion 10 of the base member 1 of the bracket acts as a brace to aid in keeping the brackets, with their attached gate section from pulling over toward the stream, such movement of the brackets and the gate 90 being further resisted by the anchoring bolts 4—4 that pass through the base members 1 and are embedded in the concrete dam wall as is clearly shown in Figure 2. 95

The several brackets for each gate or wicket section 5 are fixedly attached to the back of the said wicket or gate section by bolts 6—6 that pass through the uprights 2 of the bracket and the gate section 5 that is flatwise fixed onto the uprights 2 as shown. 100

A hinge member 7 is attached to the upper end of each of the uprights 2 and each member 7 has an inwardly and downwardly inclined flat extension 70, such extension constituting the upper connection for a collapsible brace 8, the construction of the brace 8 being best shown in Figures 1 and 2 of the drawings, by reference to which it 105

will be seen, the said brace 8 comprises an upper section 80 and a lower section 81, the upper section being composed of two strips, flatwise arranged and connected by a stud 5 pivot 9 to the extension 70 of the hinge member 7.

The lower section 81 is a single flat strip whose lower end rests flatwise upon the angled portion 10 of the base member 1 and it 10 is swivelly connected thereto, (to swing laterally with respect to said members 1 and 2) by a staple 91 that projects from the portion 10 and through an aperture 81', in the lower end of the section 81 as shown.

15 The upper or free end of the brace section 81 extends between two flat strips that constitute the upper brace section 80 and about midway the length of the brace 8 the lower section 81 is pivotally joined to the upper 20 section strips by a stud nut 12 and at its extreme upper end the brace member 81 has an outwardly projected flange 82 that constitutes a stop for limiting the lateral swing of the brace members 80 and 81, when the 25 gate section, with the uprights 2 of the bracket are swung up to the vertical position. The two brace sections 80 and 81, when the gate section is dropped in the manner presently explained, collapse by bending 30 laterally with respect to members 1 and 2 as indicated by the arrow *a* on Figure 2 and when the gate is lifted to its upright position the said brace sections 80 and 81 move laterally in the opposite direction, see ar- 35 row *b*, until they reach their fully extended alignment, to which adjustment they are limited by the stop flange 82. The two sections 80 and 81, as they reach their extended position become automatically locked and 40 are held from being collapsed until a force is applied, sufficient to pull the brace members laterally in their flatwise condition.

To provide for conveniently collapsing the brace members 8 of all of the brackets on a 45 gate section to be lowered, each flange portion 82 of the lower brace sections 81 is provided with an eye 83, and to the said eyes of the series of brackets a rod or cable 13 is swivelly attached, the connection being such 50 that a pull on the rod or cable 13 in the direction of the arrow *c* swings all of the brace sections to a collapsing position and in so doing the uprights 2 of the brackets, with their attached gate sections, are caused to 55 swing backwardly to close down over the dam top and onto the base members 1 of the brackets as is shown in Figure 2.

When the gate or wicket section is swung up, in the usual way, to increase the wall 60 height of the dam, the collapsible brace members 80 and 81 automatically assume their extended position and become interlocked to such extended position without any special manipulating of the said brack- 65 ets or the pull cable or rod 13.

The advantages of my invention will be readily apparent to and appreciated by those familiar with the care and attention of dams of the kind stated. The construction of the brackets is such that they can be easily made 70 and assembled for use by anyone familiar with construction of dams and dam gates or wicket sections. No special mechanism is required to stamp or shape up the bracket sections as they may be easily shaped up by any 75 skilled blacksmith. The cost of making the brackets and their upkeep, when operatively assembled, is so small that their use is especially desirable at places where gates or wickets are urgently needed to hold back the 80 water when rapidly rising during floods and the like.

What I claim is:

1. A wicket for dams comprising a base member adapted for being fixedly attached 85 crosswise of the dam wall top, a gate hinged to the base member to drop back onto such member and a prop connected to the gate and the base member, the said prop consisting of an upper section 90 joined to the upper edge of the gate for vertical and lateral movement with respect to the gate, and a lower section, the said lower section being swivelly connected to the base member for vertical and lateral 95 movement with respect to the said base member, operative connections pivotally joining the said prop sections to one another to swing laterally, the connections for the prop sections being such whereby to cause them 100 to fold flatwise onto the dam wall top as the prop is collapsed when the gate drops, and extend the prop sections as the gate is lifted.

2. A wicket for dams comprising a base 105 member adapted for being fixedly attached crosswise of the dam wall top, a gate hinged to the base member to drop back onto such member and a prop connected to the gate and the base member, the said prop consist- 110 ing of an upper section joined to the upper edge of the gate for vertical and lateral movement with respect to the gate, and a lower section, the said lower section being swivelly connected to the base member for 115 vertical and lateral movement with respect to the said base member, the said two prop sections being pivotally connected to one an- 120 other to swing laterally, the connection of the prop sections being such whereby the prop will fold flatwise onto the dam wall top when it collapses when the gate drops, and to assume its extended or prop adjust- 125 ment as the gate is lifted, one of the prop sections having a laterally projected flange that constitutes a stop to limit the extended adjustment of the two prop sections.

3. A wicket for dams comprising a base member adapted for being fixedly attached crosswise of the dam wall top, a gate hing- 130

edly connected to the base member to drop back onto such member and a prop connected to the gate and the base member, the said prop consisting of an upper section 5 joined to the upper edge of the gate for vertical and lateral movement with respect to the gate, and a lower section, the said lower section being swivelly connected to the base member for vertical and lateral move- 10 ment with respect to the said base member, the said two prop sections being pivotally connected to one another to swing laterally, the connections for the prop being such whereby the prop sections will fold flat- 15 wise onto the dam wall top as the gate drops, and to assume the extended or prop adjustment as the gate is lifted, one of the prop sections having a laterally projected flange that constitutes a stop to limit the 20 extended adjustment of the two prop sections, and means connected to the said flange portion for pulling the two sections to collapse them, to thereby permit the gate to drop with the collapsed prop sections onto 25 the dam wall top.

4. In a dam wicket of the character described, the combination with the wicket or gate section and the dam wall; of a plurality

of spaced props for the gate or wicket, each prop consisting of a base or sill member 30 adapted for being rigidly mounted cross- wise of the dam wall top and upright means for securing the upright to the back of the wicket or gate, a hinge joint that connects the lower end of the upright to the outer 35 end of the base member to thereby provide for dropping the gate member back onto the base or sill, a brace portion comprising an upper and lower section, the two sections being pivotally joined for swinging laterally 40 in the same directions with respect to the gate and the base member, the lower section being swivelly connected to the inner end of the base member, the upper section being likewise connected to the upper end 45 of the gate and a flexible pull connection that joins with one section of all of the props whereby to collapse all of the said props at the same time to permit the gate to drop back and cause the prop sections to 50 fall flatwise on the wall top, the said prop sections automatically resuming their extended or prop adjustments as the gate is lifted in the usual way.

WILLIAM F. KASSEBAUM.
